STOKER

Frank P. Roesch, Chicago, Ill., assignor to The Standard Stoker Company, Incorporated, a corporation of Delaware

Application September 12, 1941, Serial No. 410,669

13 Claims. (Cl. 105—234)

This invention relates to stokers and more particularly to the novel construction of the tender unit thereof and associated parts of the tender fuel bin.

The main object of the invention is to provide simple and efficient means of the type referred to above adapted to convey fuels of different grades or characteristics from a fuel bin and deliver a mixture thereof in desired proportions for combustion in a firebox. Practically all coal burning locomotives are adapted to burn bituminous coal. There are in certain regions vast stores of inexpensive anthracite culm that could be utilized under suitable conditions by railroads operating through these regions. Anthracite culm alone cannot be successfully burned in present day locomotives, though it has been successfully used when hand fired in certain proportions along with bituminous coal. While the proportions may vary over a considerable range, a mixture consisting of up to as high as 50 percent anthracite culm can be very successfully burned.

While such mixtures could be successfully burned when hand fired, considerable difficulty was experienced in mechanical firing, for even when anthracite culm or buck and bituminous coal was thoroughly mixed in the tender fuel bin, segregation occurred; the anthracite moving toward the bottom of the pile. This segregation is accentuated in the tender due to oscillation and vibration when running.

As a more specific object, the invention contemplates means whereby fuels of different characteristics are separately conveyed from separate compartments of a fuel bin, mixed in transit to a firebox in desired proportions, and mixture delivered to a firebox.

A still further object of the invention is to provide a stoker of the type described above wherein fuels of different grades or characteristics are separately conveyed from separate sources, mixed in transit and delivered to a firebox in desired predetermined proportions, and which stoker is adapted without alteration or adjustment to separately convey from separate sources, mix in transit and deliver a mixture of similar kinds of fuel to a firebox.

With these and other objects in view, the invention consists of the features of construction, combination and arrangement of parts, herein-after fully described and claimed, reference being had to the accompanying drawings.

For purpose of illustration the invention is described as applied to a locomotive and tender and with reference to mechanical feeding of bitu-

minous coal and anthracite culm, however, it will be apparent that the invention is equally adaptable for feeding fuel from a fuel bin to fireboxes of other types and adaptable for feeding mixtures of other kinds of fuels.

In the drawings,

Fig. 1 is a view in side elevation of the adjacent end portions of a locomotive and tender with the novel stoker applied thereto, the side wall of the tender being removed to show the interior of the fuel bin and that portion of the stoker mounted in the tender;

Fig. 2 is a plan view of the forward end of the tender with the stoker applied thereto, parts being broken away;

Fig. 3 is a view in section taken on the line 3—3 of Fig. 2;

Fig. 4 is a view in section taken on the line 4—4 of Fig. 3;

Fig. 5 is an end elevation of the gear housing at the rear of the stoker with the cover removed to show the gearing, parts being broken away; and

Fig. 6 is a view in section taken on the line 6—6 of Fig. 5, with the gear housing cover applied thereto.

Referring to Fig. 1, the letter L designates a locomotive, T a tender and S a stoker for delivering fuel from the tender to the locomotive. The locomotive and the forward end of the stoker is not shown in the remaining figures since the novel construction resides in the tender fuel bin and the tender unit of the stoker. The stoker front end arrangement shown in Fig. 1 is shown for purpose of illustration only and any of the various stoker front end arrangements, well known in the art, may be used with my novel tender fuel bin and stoker tender unit.

The tender T comprises a water compartment 10 and a fuel bin 11 separated by a transversely extending upright partition 12 forming the rear wall of the tender fuel bin 11. The sides of the fuel bin 11 are defined by the upper portions of the tender side sheets 13 and 14 and the side slope sheets 15 and 16, respectively, as best shown in Fig. 4.

The fuel bin 11 is divided into two compartments 17 and 18, by an upright longitudinally extending partition plate 19. An angle iron 20 is secured in any suitable manner to the lower edge of the partition plate 19 in an inverted V position and a T shaped beam 21, extending longitudinally the length of the tender fuel bin 11 midway between the sides thereof, is secured in any suitable manner to the fuel bin floor 22 in an inverted position. The free end of the up-

right portion of the inverted T shaped beam is received in the apex of the inverted V shaped angle iron 20, whereby the partition plate 19 is supported in a manner to swing about its lower edge as an axis.

Means best shown in Fig. 4, is provided for retaining the partition plate 19 in a vertical position, dividing the fuel bin 11 into two equal compartments, and for retaining it in a number of angular positions, one such position being shown in dot and dash, dividing the bin 11 into two unequal compartments. This means comprises, at the rear of the bin 11, a pair of overlapping arms 23 and 24 secured together by a pair of spaced pins 25 and 26 extending through the overlapped portion of the arms 23 and 24. The end of the arm 23 opposite its overlapped portion is attached by a pin 27 to an angle 28 which is secured to the partition plate 19; and the end of the arm 24 opposite its overlapped portion is attached by a pin 29 to an angle 30 which is secured to the tender side sheet 14. The pins 26 and 29 are removable so that the arm 23 can be attached to the lower portion of the angle 30, as shown in dot and dash in Fig. 4, whereby the partition plate 19 will assume an angular position increasing the area of compartment 17 and decreasing the area of compartment 18. The relative areas of the compartments 17 and 18 can also be varied by attaching the arm 23 to the upper portion of the angle 30 and by providing additional openings in the angle 30 adapted to receive either the pin 26 or pin 29. A similar arrangement is provided at the forward end of the fuel bin, the overlapping arms being shown in Fig. 2 at 23' and 24', and the respective angles to which they are attached at 28' and 30'. A stop 31 is secured to the rear wall 12 of the fuel bin to prevent the partition plate 19 moving beyond its vertical position toward the tender side sheet 13.

The fuel bin floor 22 is provided at each side of the partition plate 19 with a longitudinally elongated opening; the opening 32 forming a fuel outlet for the compartment 17 and the opening 33 forming a fuel outlet for the compartment 18. Beneath the opening 32 is a trough 34 arranged to receive fuel from the compartment 17 and beneath the opening 33 is a trough 35 arranged to receive fuel from the compartment 18. The openings 32 and 33 may be closed when desired by a plurality of slidably mounted plates 36 and 37, respectively, which are so arranged that they may be drawn forward one at a time as the coal is consumed to present a relatively small opening in the desired position in the floor of the bin.

A return bend conduit 38 communicates at its opposite open ends with the forward ends, respectively, of the troughs 34 and 35, and is provided with a back outlet opening 39. The return bend conduit 38 communicates through its back outlet opening 39 with the spherical extension or bowl 40 which is received in a spherical portion 41, as shown in Fig. 1, of the rear tubular section 42 of the intermediate conduit 43. The front section 44 of this conduit telescopes with the rear section 42 and at its forward end is connected by a universal joint 45 with the lower end of a riser conduit or discharge box 46. The upper forward end of the riser conduit 46 communicates with the locomotive firebox.

Screw conveyors 47 and 48 are mounted in the troughs 34 and 35 for advancing fuel therethrough into the return bend conduit 38. The forward ends of the screw conveyors 47 and 48

preferably extend a short distance into the return bend conduit 38 for facilitating movement of the fuel therethrough toward the back outlet opening 39. A screw conveyor 49, keyed to a shaft 50 journaled in the wall of the return bend conduit 38 opposite the outlet opening 39, extends forwardly through the opening 39 into the bowl 40 and advances the fuel delivered by the screw conveyors 47 and 48. Screw conveying means, not shown, connected in a manner well known in the art to the forward end of the screw conveyor 49 advances fuel through the intermediate conduit 43 and riser 46 to the locomotive firebox. The screw conveyors 47, 48 and 49 are arranged with their axes in the same horizontal plane. Crushers 51 and 52 arched over the conveyor screws 47 and 48, respectively, at the forward end of the troughs 34 and 35, respectively, cooperate with the conveyor screws 47 and 48, respectively, to crush the larger lumps of coal to a size suitable for firing.

The screw conveyors 47, 48 and 49 are adapted to be operated through reduction gearing located in the gear housing 53 at the rear of the troughs 34 and 35 from a suitable source of power, such as the two cylinder reciprocating steam engine 54. The engine 54 is shown mounted on the tender but it is obvious that it may be mounted on the locomotive if desired with suitably designed shafting, well known in the art. A telescopic drive shaft 55 is preferably flexibly connected at one end to the engine and at its other end flexibly connected with the pinion shaft 56 of the gearing so that it may have the necessary expanding, contracting and flexing motions under running conditions of the tender.

The gearing enclosed in the gear housing 53 and cover 57 comprises the pinion shaft 56 driven by the drive shaft 55; the shaft 58 for driving the screw conveyor 47; the shaft 59 coupled to the shaft 60, extending between the troughs 34 and 35, which in turn is coupled to the shaft 50 for driving the screw conveyor 49; the shaft 61 for driving the screw conveyor 48; intermeshing pinion gear 62 and gear 63 on shafts 56 and 58, respectively; intermeshing gears 64 and 65 on shafts 58 and 59, respectively; and intermeshing gears 66 and 67 on shafts 59 and 61, respectively.

For reasons hereinafter set forth, the gearing is arranged so that the screw conveyor 49 operates one and one half times as fast as the screw conveyor 47 and the screw conveyor 48 operates about one fourth as fast as the screw conveyor 47. The present invention contemplates the feeding of mixtures of bituminous coal and anthracite culm, the bituminous coal being contained in the compartment 17 and conveyed by the screw conveyor 47 and the anthracite culm being contained in the compartment 18 and conveyed by the screw conveyor 48. The bituminous coal most generally used by the railroads is run-of-mine coal, and since this comprises a considerable percentage of large lumps, less of this coal will be delivered per revolution of the screw conveyor than of the anthracite culm. Thus, while the anthracite conveying screw 48 operates about one fourth as fast as the bituminous conveying screw 47, actually the ratio of bituminous coal to anthracite culm delivered will be about three to one. A mixture in these proportions can be burned very successfully, but it will be understood that they may be burned in other proportions if desired, and can be conveyed in the desired proportions by changing the gear ratios.

It is also apparent that the capacity of the stoker can be increased by altering the gear ratios to operate the screw conveyor 48, at a rate approaching or equal to the rate of the screw conveyor 47 and appropriately increasing the feeding capacity of screw conveyor 49 by changing the gear ratio or increasing the diameter of the screw or both. This is particularly advantageous when it is desired to feed all bituminous coal and greater capacity is desired.

In Fig. 4 the partition plate 19 is shown dividing the fuel bin 12 into equal compartments but as explained above, the plate 19 can be adjusted to any one of a number of positions to vary the relative sizes of the compartments 17 and 18. Thus, if the gear ratios and the characteristics of the fuel being conveyed are such that the screw conveyor 47 will convey about three times as much fuel as the screw conveyor 48, then the partition plate 19 can be adjusted to a position making the capacity of the compartment 17 about three times that of compartment 18, so that the one compartment will not empty before the other. While the invention is particularly adaptable for conveying fuels of different characteristics it is apparent that fuel of the same kind can be placed in the compartments 17 and 18 and conveyed, without making any alterations or adjustments in the construction.

The fuel conveyed by the screw conveyors 47 and 48 is urged through the return bend conduit 38 to the screw conveyor 49, where it is mixed and conveyed forwardly into the bowl 40. Suitable conveying means delivers the mixed fuel through the intermediate conduit 43 and riser 46 to the firebox.

I claim:

1. The combination in a locomotive tender, of a fuel bin for said tender, a floor for said fuel bin, means extending longitudinally within said fuel bin dividing the latter into two compartments, said floor being provided with a longitudinally elongated opening at each side of said dividing means through which fuel drops by gravity from said compartments, a conduit system including a longitudinally extending trough portion beneath each of said compartments arranged to receive fuel therefrom through said openings and a tubular portion forward of and connecting the forward ends of said trough portions, said tubular and trough portions lying in substantially the same horizontal plane, and conveying means in each of said trough portions for advancing fuel therethrough into said tubular portion, said tubular portion having an opening providing a common outlet for fuel delivered from both said trough portions.

2. The combination in a locomotive tender, of a fuel bin having a floor, said floor being provided with a pair of longitudinally elongated laterally spaced openings through which fuel drops by gravity from said fuel bin, a longitudinally extending trough conduit beneath each of said openings for receiving fuel from said fuel bin, a return bend conduit forward of and connecting the forward ends of said trough conduits, said return bend conduit being provided with a back outlet opening, conveying means in each of said trough conduits for advancing fuel therethrough into said return bend conduit and conveying means in said return bend conduit for conveying fuel therefrom through said back outlet opening.

3. The combination in a locomotive tender, of a fuel bin having a floor, said floor being pro-

vided with a pair of longitudinally elongated laterally spaced openings through which fuel drops by gravity from said fuel bin, a longitudinally extending trough conduit beneath each of said openings for receiving fuel from said fuel bin, a return bend conduit connecting the forward ends of said trough conduits, said return bend conduit being provided with a back outlet opening, a screw conveyor in each of said trough conduits for advancing fuel therethrough into said return bend conduit, and a screw conveyor in said return bend conduit for conveying fuel therefrom through said back outlet opening.

4. The combination in a locomotive tender, of a fuel bin for said tender, a floor for said fuel bin, means extending longitudinally within said fuel bin dividing the latter into two compartments, said floor being provided with a longitudinally elongated opening at each side of said dividing means through which fuel drops by gravity from said compartments, a longitudinally extending trough conduit beneath each of said compartments arranged to receive fuel therefrom through said openings, a return bend conduit forward of and connecting the forward ends of said trough conduits, said return bend conduit being provided with a back outlet opening, conveying means in each of said trough conduits for advancing fuel therethrough into said return bend conduit and conveying means in said return bend conduit for conveying fuel therefrom through said back outlet opening.

5. The combination in a locomotive tender, of a fuel bin for said tender, a floor for said fuel bin, means extending longitudinally within said fuel bin dividing the latter into two compartments, said floor being provided with a longitudinally elongated opening at each side of said dividing means through which fuel drops by gravity from said compartments, a longitudinally extending trough conduit beneath each of said compartments arranged to receive fuel therefrom through said openings, a return bend conduit connecting the forward ends of said trough conduits, said return bend conduit being provided with a back outlet opening, a screw conveyor in each of said trough conduits for advancing fuel therethrough into said return bend conduit, and a screw conveyor in said return bend conduit for advancing fuel, and a screw conveyor journaled in the wall of said return bend conduit opposite said back outlet opening, said last named screw conveyor ex-

tending forwardly through said back outlet opening.

7. The combination in a locomotive and tender, of a fuel bin for said tender, a floor for said fuel bin, means extending longitudinally within said fuel bin dividing the latter into two compartments, said floor being provided with a longitudinally elongated opening at each side of said dividing means through which fuel drops by gravity from said compartments, a longitudinally extending trough conduit beneath each of said compartments arranged to receive fuel therefrom through said openings, a return bend conduit connecting the forward ends of said trough conduits, said return bend conduit being provided with a back outlet opening, a transfer conduit extending forwardly from said back outlet opening to the locomotive, a screw conveyor in each of said trough conduits extending into said return bend conduit for advancing fuel, a screw conveyor journaled in the wall of said return bend conduit opposite said back outlet opening, said last named screw conveyor extending forwardly through said back outlet opening, and a screw conveyor in said transfer conduit operatively connected at its rearward end with the forward end of said last named screw conveyor.

8. The combination in a locomotive and tender, of a fuel bin for said tender, a floor for said fuel bin, means extending longitudinally within said fuel bin dividing the latter into two compartments, said floor being provided with a longitudinally elongated opening at each side of said dividing means through which fuel drops by gravity from said compartments, a longitudinally extending trough conduit beneath each of said compartments arranged to receive fuel therefrom through said openings, a return bend conduit connecting the forward ends of said trough conduits, said return bend conduit being provided with a back outlet opening, a transfer conduit extending forwardly from said back outlet opening to the locomotive, a screw conveyor in each of said trough conduits extending into said return bend conduit for advancing fuel, a screw conveyor journaled in the wall of said return bend conduit opposite said back outlet opening, said last named screw conveyor extending forwardly through said back outlet opening, the axes of said screw conveyors all lying in the same horizontal plane.

9. The combination in a locomotive tender, of a fuel bin having a floor, said floor being provided with a pair of longitudinally elongated laterally spaced openings through which fuel drops by gravity from said fuel bin, a longitudinally extending trough conduit beneath each of said openings for receiving fuel from said fuel bin, a return bend conduit connecting the forward ends of said trough conduits, said return bend conduit being provided with a back outlet opening, a screw conveyor in each of said trough conduits for advancing fuel therethrough into said return bend conduit, a screw conveyor in said return bend conduit for conveying fuel therefrom through said back outlet opening, means for driving said screw conveyors including gearing at the rear of said trough conduits, a pair of shafts operatively connecting said gearing with each of the trough conduit screw conveyors, and a shaft extending longitudinally between said trough conduits operatively connecting said gearing and the screw conveyor in said return bend conduit.

10. The combination in a locomotive tender, of a fuel bin for said tender, a floor for said fuel bin, means extending longitudinally within said fuel bin dividing the latter into two compartments, said floor being provided with a longitudinally elongated opening at each side of said dividing means through which fuel drops by gravity from said compartments, a longitudinally extending trough conduit beneath each of said compartments arranged to receive fuel therefrom through said openings, a return bend conduit connecting the forward ends of said trough conduits, said return bend conduit being provided with a back outlet opening, a screw conveyor in each of said trough conduits for advancing fuel therethrough into said return bend conduit, a screw conveyor in said return bend conduit for conveying fuel therefrom through said back outlet opening, means for driving said screw conveyors including gearing at the rear of said trough conduits, a pair of shafts operatively connecting said gearing with each of the trough conduit screw conveyors, and a shaft extending longitudinally between said trough conduits operatively connecting said screw conveyor in said return bend conduit.

11. The combination in a locomotive tender, of a fuel bin having a floor, a longitudinally extending inverted T shaped beam secured to said floor, a longitudinally extending upright partition dividing said fuel bin into two compartments, said partition having an inverted V shaped angle extending along its lower edge, the upper edge of the upright portion of said inverted T shaped beam being received in the apex of said inverted V shaped angle providing for swinging movement of said partition about its lower edge as an axis to vary the relative capacities of said compartments, and means for retaining said partition in any one of a number of positions.

12. The combination in a locomotive tender, of a fuel bin, a pair of longitudinally extending trough conduits disposed side by side at the bottom of said bin for receiving fuel therefrom, a return bend conduit connecting the forward ends of said trough conduits, said return bend conduit being provided with a back outlet opening, a screw conveyor in each of said trough conduits for advancing fuel therethrough into said return bend conduit, and a screw conveyor in said return bend conduit for conveying fuel therefrom through said back outlet opening, said conduits being arranged with the screw conveyors therein all lying in the same horizontal plane.

13. The combination in a locomotive tender, of a fuel bin, a pair of longitudinally extending trough conduits disposed side by side at the bottom of said bin for receiving fuel therefrom, a tubular conduit connecting the forward ends of said trough conduits, a screw conveyor in each of said trough conduits for advancing fuel therethrough into said tubular conduit, said tubular conduit having an opening providing a common outlet for fuel delivered from both said trough conduits, a third screw conveyor for conveying fuel forwardly from said common outlet, means for driving said screw conveyors including gearing at the rear of said trough conduits, a pair of shafts operatively connecting said gearing with each of the trough conduit screw conveyors, and a shaft extending longitudinally between said trough conduits operatively connecting said gearing and said third screw conveyor.

FRANK P. ROESCH.
